US00D859395S

(12) **United States Design Patent** (10) **Patent No.:** **US D859,395 S**
(45) **Date of Patent:** **** Sep. 10, 2019**

(54) **PORTABLE DEVICE HOLDER**

- (71) Applicant: **Kenu, Inc.**, San Francisco, CA (US)
(72) Inventors: **David E. Yao**, San Francisco, CA (US);
Leonard John Duran, Mill Valley, CA (US); **Gregory D. Canear**, Oakland, CA (US); **Kenneth Y. Minn**, San Francisco, CA (US)
(73) Assignee: **Kenu, Inc.**, San Francisco, CA (US)
(**) Term: **15 Years**

(21) Appl. No.: **29/638,303**

(22) Filed: **Feb. 26, 2018**

(51) LOC (12) Cl. **14-03**

(57) **CLAIM**

The ornamental design for a portable device holder, as shown and described.

DESCRIPTION

FIG. 1 is a rear perspective view of a portable device holder; FIG. 2 is a front perspective view of the portable device holder;

FIG. 3 is a front elevational view of the portable device holder;

FIG. 4 is a rear elevational view of the portable device holder;

FIG. 5 is a bottom plan view of the portable device holder;

FIG. 6 is a top plan view of the portable device holder;

FIG. 7 is a right elevational view of the portable device holder; and,

FIG. 8 is a left elevational view of the portable device holder.

Portions of the portable device holder shown in broken lines in FIG. 5 form no part of the claimed design.

1 Claim, 2 Drawing Sheets
